UNITED STATES PATENT OFFICE

112,836

DESIGN FOR AN ELECTRIC FAN

Arley U. Hook, Fostoria, Ohio, assignor to Bersted Manufacturing Company, Fostoria, Ohio, a corporation of Ohio

Application March 23, 1938, Serial No. 76,034

Term of patent 7 years

To all whom it may concern:

Be it known that I, Arley U. Hook, a citizen of the United States and resident of Fostoria, in the county of Seneca and State of Ohio, have invented a new, original, and ornamental Design for an Electric Fan, of which the following is a specification, reference being had to the accompanying drawing, forming a part thereof.

Fig. 1 is a perspective view of an electric fan showing my new design; Fig. 2 is a sectional view

thereof taken on the line 2—2 in Fig. 1, and Fig. 3 is a plan of the base taken on the section 3—3 in Fig. 2.

The dominant features of my design are shown in solid lines in the drawing.

I claim:

The ornamental design for an electric fan, substantially as shown and described.

ARLEY U. HOOK.
